UNITED STATES PATENT OFFICE.

FRANK T. DICKINSON, OF TOLEDO, OHIO.

TOY SAND MOLD.

Application filed April 21, 1925. Serial No. 24,766.

The present invention is directed to improvements in toy sand molds.

The primary object of the invention is to provide a device of this character so constructed that miniature houses, bridges, etc., can be molded from moist sands and mold parts removed leaving the molded article standing in a substantial manner.

A further object of the invention is to provide a mold of this kind constructed and arranged in such manner that the parts thereof may be united to mold a single one story building or a row of buildings either of a single story or of several stories, as may suit the fancy of the user.

A still further object of the invention is to provide a mold of this nature so constructed that the mold parts can be easily and quickly set up for use and readily disassembled after the mold has been tamped sufficiently to enable the article molded to stand.

Still another object of the invention is to provide a mold of this type so constructed that the sand can be tamped therein without danger of the parts or plates bulging or shifting during the tamping operation.

The molds are primarily designed for use on sand beaches and will not only furnish amusement for children, but will be instructive as well. It will be of course obvious that the device is not limited for beach use, but can be used in play rooms, schools or in any place where art and designing is taught.

With these and other objects in view, this invention resides in the novel features of construction, formation, combination and arrangement of parts to be hereinafter more fully described, claimed and illustrated in the accompanying drawings, in which:—

Figure 1 is a perspective view of the mold for forming a single story house.

Figure 2 is a similar view, showing the mold arranged for forming a row of single story houses.

Figure 3 is a side view of a pair of side plates arranged for forming a two story house.

Figure 4 is a sectional view on line 4—4 of Figure 1.

Figure 5 is a perspective view of a modified form of the invention arranged for forming bridges.

Figure 6 is a perspective view of the striker plate used in connection with bridges.

Figure 7 is a perspective view of the core.

Figure 8 is a perspective view of the step mold.

Figure 9 is a modified form, showing means for detachably connecting certain of the mold plates.

As shown in Figure 1 of the drawings, the mold is assembled for producing a single one story house or building, the mold consisting of side and end plates 1 and 2, respectively, the latter having their upper ends terminating in gable portions 3.

The side edges of the end plates 2 are provided with sleeves 4 and 5, respectively, the latter being arranged in vertically spaced pairs. The side edges of the end plates are provided with sleeves 6 and 7 arranged in a manner similar to the sleeves of the side plates and with which they co-operate when in registry to receive the metal anchor pins 8. These pins when in place not only serve to interlock or connect the adjacent ends of the respective plates, but also serve to anchor the plates due to the fact that their lower ends penetrate the ground. Since these pins firmly anchor the mold, damp sand can be tamped therein without danger of the plates shifting. In Figure 2 of the drawings the plates are connected so that a row of houses can be formed and it will be, of course, understood that the plates can be arranged so that a number of different effects can be obtained.

The side plates 1 have their upper and lower edges terminating in right angle, outwardly extending flanges 9 and 10, respectively, the former having seats 11 formed therein, while the latter have lugs 12 pressed therein and adapted to detachably engage the seats 11 when the plates are superposed for molding houses of two or more stories.

The plates 1 and 2 are further provided with impressions 13 and 14, respectively, so that when the plates are removed after the molding operation the molded articles will have impressed therein simulations of doors and windows, which will add greatly to the natural appearance of the molded article. It will be of course understood that when one story houses are molded that the side plates 1 are used for the lower story, the uppermost story requiring the use of gabled end plates. When houses of two or more stories are molded the plates 1 are placed

with their flanges 9 and 10 in interlocked relation through the medium of the seats 11 and lugs 12. In this manner shifting of the plates is positively prevented.

5 Assuming that the plates 1 and 2 are in set up positions, as shown in Figure 1 of the drawings and with the pins 8 embedded in the beach foundation moist sand is tamped in the mold thus formed, after which the sand is scraped off even with the gables 3 of the end plates to form a slanting roof. The pins 8 are then removed to permit disengagement of the plates, thus leaving a complete house standing with simulations of doors and windows formed therein through the medium of the impressions 13 and 14. A mold 15 is used to form a chimney upon the ridge of the roof of the completed house 16.

20 In the modified form of the invention as shown in Figure 7 of the drawings, the mold is shown for forming arched bridges, the side plates 17 thereof having semi-circular cut-outs 18 formed, the upper edges of said plates terminating in inwardly directed horizontal flanges 19, the purpose of which will appear later. These plates have loops 20 upon their outer surfaces and in which the pins 21 are detachably engaged and since 25 they engage the beach foundation the plates will be firmly anchored in proper spaced relation. Operating in conjunction with the plates 17 are cores 22 which are semi-circular in cross-section and are designed to have 30 their ends engage the cut-outs 18 during the molding operation. In operation the plates 17 are anchored in proper spaced relation with the cores 22 in position, after which moist sand is tamped in the mold thus 35 formed. The cores are provided with handles 23 to facilitate the removal thereof. Used in connection with this mold is a strike plate 24 having an extension plate 25. The strike plate is placed at one end of the mold and drawn lengthwise thereof so that the extension plate 25 will remove the sand and 40 form a groove 26, the sides of which constitute sides 27 for the bridge. Owing to the presence of the flanges 19 the sides 26 will remain intact with their upper surfaces 45 smooth upon removal of the side plates and cores. To make bridges of various lengths the plates and cores may be moved along as each section is molded. After a bridge of 50

the desired length has been molded the approaches thereto can be enhanced by the steps formed by the mold 27 shown in Figure 8.

55 It will be obvious that by minor changes in the shape of the respective plates and rearrangement thereof that forts, castles, monuments, ships and towers can be molded.

60 In the modified form of the invention as shown in Figure 9, the flanges 28 of the plates 29 are provided with perforations 30 65 which are adapted to register when the plates are superposed for receiving the locking pins 31. This means for interlocking the plates may be used in lieu of the seats 11 and lugs 12, if desired. The plates 29 like 70 those of the preferred form of the invention are provided upon their ends with sleeves 32 and 33 adapted to be engaged by the comparatively short pins 31. It will be observed that these pins are of such length 75 as to be used with each set of plates, whereas the pins 8 are designed to penetrate a foundation, and are common to two or more sets when superposed. Since the device may be used on platforms or tables it is not necessary in all instances to have the pins of such length as to penetrate a foundation. 80

85 What is claimed is:—

1. A toy sand mold comprising a plurality of side and end plates, the end plates being capable of being detachably secured 90 end to end to simulate the front and rear walls of a row of sand houses, the side plates being adapted to have their ends detachably secured to the outer ends of the outermost end plates to simulate outer side walls of each end house of the row.

95 2. A toy sand mold consisting of a plurality of side and end plates, the end plates being capable of being detachably secured end to end, said side plates being adapted to have their ends detachably secured to the ends of the outermost end plates, said side and end plates having flanges upon their longitudinal edges for engagement with 100 each other when the plates are placed in superposed relationship, said flanges being provided, respectively, with seats and lugs for interlocking engagement.

105 In testimony whereof I affix my signature.

FRANK T. DICKINSON.
